LIQUID AND PASTE DISPENSER
Candido Jacuzzi, Lafayette, Calif., assignor to Jacuzzi
Bros., Incorporated, a corporation of California
Filed Sept. 17, 1965, Ser. No. 488,062
2 Claims. (Cl. 222—183)

ABSTRACT OF THE DISCLOSURE

A liquid and paste dispenser of the aerosol type where-
in the container is vented to the atmosphere and the con-
tents are confined to an expandable tube which encloses
a stem having a passage to a control valve, the expandable
tube being preferably prestressed to snugly fit the stem in
the absence of any dispensable contents in such tube.

My invention relates to liquid and paste dispensers,
and more particularly to a dispenser which functions by
reason of self-contained pressure.

In the general category to which the present invention
relates are the aerosol dispensers. While they function
by reason of a self-contained source of pressure,
such source involves gas under such high pressure that
not only are the bottoms of the dispensing cans made
concave to withstand such pressures, but the instruc-
tions on each dispenser warn against explosion should
the same be exposed to high temperatures or other
abuses. Also, such dispensers are limited as to orienta-
tion in dispensing.

Among the objects of my invention are:

(1) To provide a novel and improved dispensing
means for liquids and pastes;

(2) To provide a novel and improved dispensing
means for liquid and pastes which will function by
reason of self-contained pressure, but will not present the
hazards of explosion;

(3) To provide a novel and improved liquid and
paste dispenser of the aerosol type but one which is free
of the hazards encountered in the use of such dispensers;

(4) To provide a novel and improved liquid and paste
dispenser of simple construction, and one which is cap-
able of dispensing the entire contents thereof under
pressure.

(5) To provide a novel and improved liquid and paste
dispenser which can dispense without regard to its position
or orientation.

Additional objects of my invention will be brought
out in the following description of a preferred embodiment
of the same, taken in conjunction with the accom-
panying drawings wherein

FIGURE 1 is a view in section through a dispenser
embodiment of the present invention, depicted in its condition
prior to filling;

FIGURE 2 is a corresponding view depicting the dis-
penser when filled; and

FIGURE 3 is a three dimensional view of a liquid
displacement rod or stem constituting an important com-
ponent of the dispenser as illustrated in FIGURES 1
and 2.

Referring to the drawings for details, the specific em-
bodiment illustrated comprises a closed receptacle 1
including a container 3 and a cover 5 therefor. The con-
tainer is closed at its lower end and is preferably formed
of one piece with the closed end or bottom hemispherical.

The cover may be of a plug type, and provided with a
hollow depending neck 7 centrally thereof and forming
a continuation of a passageway 9 through the cover.
One or more vent passageways 11 through the cover
place the interior of the container in permanent com-
munication with the external atmosphere.

2

Encircling the upper end of the container is a retain-
ing ring 13 serving to maintain the container at its rim,
in snug fitting engagement with the plug type cover 5.

Affixed at one end within the neck, is a rod or stem
5 15, having a longitudinal channel or groove 17 extending
preferably the full length thereof and terminating at
its upper end in communication with the passageway
through the cover.

Installed over the stem, is an expandable tube 21, closed
at its lower end, and sealed at its otherwise open end
about the neck, by any suitable hose type clamp 22. This
expandable tube is preferably of less diameter than the
stem and is installed in partially stressed condition, so
as to snugly hug the stem under pressure.

10 In the passageway through the cover, there is installed
a manually operable normally closed valve means of
any suitable character, capable on opening of the valve,
to complete a flow passageway from the interior of the
expandable tube through the stem and cover to external
atmosphere. One form of valve means suitable for pur-
pose might be that employed in conventional aerosol
dispensers, and such type of valve is illustrated in the
drawings.

Briefly, the valve means comprises an inner compo-
25 nent 25 having a counterbored passageway 25 there-
through in communication with the channel or groove 17
in the stem, the counterbore to house a spring biased
valve in the form of a collar 29 mounted on the end of
30 a hollow valve stem or tube 31 extending upwardly be-
yond the exposed end of the cap, the proximate end of
the tube being closed by a plug 33. The valve, under
pressure of a spring 35, is adapted to seat against a disc
37 retained in contact with the inner component 25 of
35 the valve means, by a valve retaining ring 39 set into the
cover and having a central passageway of sufficient di-
ameter to permit free movement of the valve tube.

The valve is adapted to be depressed by pressure on
the exposed end of the tube, and by providing a small
opening 43 in the tube above but in proximity to the
40 valve seat disc 37, the interior of the expandable tube 21
may be brought into flow communication with the atmos-
phere by depressing the valve sufficiently to bring the
perforation below the valve seat. A decorative spray cap
45 mounted on the exposed end of the tube and having
45 a passageway 47 therethrough connecting with the tube,
permits of the application of finger pressure to the tube
to provide for such opening of the valve.

Should a fine spray discharge or aerated foam be de-
sired, an aspirator may be incorporated in the cap, in
50 the form of a venturi in the passageway 47 and a vent
connecting therewith. By covering the vent, a liquid or
paste discharge may be re-established.

In preparing the dispenser for use, the contents will
55 be introduced under pressure through the tube 31 prior
to the installation of the spray cap, which filling may be
accomplished by holding the tube depressed during such
filling operation. The introduction of such contents under
pressure, will cause the expandable tube to expand as it is
being filled, until the same contacts the container, at which
60 time the filling mechanism will be withdrawn, whereupon
the valve will automatically close to retain the contents
under pressure. Upon application of the spray cap, the
contents of the dispenser may be dispensed at will and in
desired quantity, merely by depressing the same as one
65 would the cap on an aerosol dispenser.

In this connection, it is important to note that the con-
tents of the dispenser of the present invention has no
expansile characteristics, and therefore has no inherent
property to exhibit any pressure on its own. The only
70 element stressed and to which pressure may be attributed,
is the expandable tube 21, unless perchance, the tube is
over-filled to the point where the contents brings pressure

to bear against the container itself, it being noted that any air in the container is automatically expelled through the air vents during filling, and consequently no gas under pressure will exist at any time within the container.

Accordingly, pressure against the contents of the expansible tube can be attributed solely to the tube itself, unless the dispenser happens to be over-filled, in which case some pressure may be attributable to the container itself, while under stress. In either event however, all pressures are directed inwardly and consequently, risks of explosion are non-existent.

While the expansible tube 21 might be installed loosely instead of under stress as previously described, it is to be noted that by installing it under stress, complete evacuation of the contents thereof may be realized, for the expansible tube will continue to exert pressure against its contents until the tube actually pressure engages the stem, by which time the entire contents of the tube will have been dispensed.

From the foregoing description of my invention in its preferred form, it will be apparent that the same is subject to alteration and modification without departing from the underlying principles involved, and I accordingly, do not desire to be limited in my protection to the specific details illustrated and described, except as may be necessitated by the appended claims.

I claim:

1. A liquid and paste dispenser comprising a closed receptacle including a container and cover therefor, and having an air vent, a stem of substantially uniform cross section extending into said receptacle from said cover end, an expansible tube, closed at its bottom end and enclosing said stem and sealed about said stem at its

otherwise open end, said stem extending downwardly substantially to the bottom of said tube, said expansible tube, in its unstressed condition, having an internal periphery less than the outside periphery of said stem, whereby in its empty condition, said tube will, while still in stressed condition, engage said stem to assure substantially complete dispensing of its dispensable contents outwardly from the periphery of said stem, said tube being expandable to substantially the capacity of said receptacle when filled with dispensable contents,

a flow passageway from the interior of said tube through said stem and cover to external atmosphere, and manually operable normally closed valve means in said cover, blocking said passageway.

2. A dispenser according to claim 1 wherein said stem is provided with a longitudinal slot in its outer periphery extending substantially the entire length thereof.
